(57) **CLAIM**

We claim the ornamental design for a baking pan, as shown and described.

DESCRIPTION

FIG. 1 is a perspective view of a baking pan according to the new design;

FIG. 2 is a top view of the baking pan shown in FIG. 1;
FIG. 3 is a front view of the baking pan shown in FIG. 1;
FIG. 4 is a rear view of the baking pan shown in FIG. 1;
FIG. 5 is a left side elevation view of the baking pan shown in FIG. 1;

FIG. 6 is a right side elevation view of the baking pan shown in FIG. 1;

FIG. 7 is a bottom view of the baking pan shown in FIG. 1;
FIG. 8 is a perspective view of another embodiment of a baking pan according to the new design;

FIG. 9 is a top view of the baking pan shown in FIG. 8;
FIG. 10 is a front view of the baking pan shown in FIG. 8;
FIG. 11 is a rear view of the baking pan shown in FIG. 8;
FIG. 12 is a left side elevation view of the baking pan shown in FIG. 8;

FIG. 13 is a right side elevation view of the baking pan shown in FIG. 8; and,

FIG. 14 is a bottom view of the baking pan shown in FIG. 8.

The broken lines shown in the drawing is for illustrative purposes only and forms no part of the claimed design.
